Application August 14, 1933, Serial No. 684,938

26 Claims. (Cl. 12—142)

This invention relates to improvements in methods of securing together pieces of material, for example shoe parts and the like, and is disclosed herein with particular reference to the attachment of soles to shoes.

Present-day practice in the manufacture of ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ ²³⁵ ²⁴⁰ ²⁴⁵ ²⁵⁰ ²⁵⁵ ²⁶⁰ ²⁶⁵ ²⁷⁰ ²⁷⁵ ²⁸⁰ ²⁸⁵ ²⁹⁰ ²⁹⁵ ³⁰⁰ ³⁰⁵ ³¹⁰ ³¹⁵ ³²⁰ ³²⁵ ³³⁰ ³³⁵ ³⁴⁰ ³⁴⁵ ³⁵⁰ ³⁵⁵ ³⁶⁰ ³⁶⁵ ³⁷⁰ ³⁷⁵ ³⁸⁰ ³⁸⁵ ³⁹⁰ ³⁹⁵ ⁴⁰⁰ ⁴⁰⁵ ⁴¹⁰ ⁴¹⁵ ⁴²⁰ ⁴²⁵ ⁴³⁰ ⁴³⁵ ⁴⁴⁰ ⁴⁴⁵ ⁴⁵⁰ ⁴⁵⁵ ⁴⁶⁰ ⁴⁶⁵ ⁴⁷⁰ ⁴⁷⁵ ⁴⁸⁰ ⁴⁸⁵ ⁴⁹⁰ ⁴⁹⁵ ⁵⁰⁰ ⁵⁰⁵ ⁵¹⁰ ⁵¹⁵ ⁵²⁰ ⁵²⁵ ⁵³⁰ ⁵³⁵ ⁵⁴⁰ ⁵⁴⁵ ⁵⁵⁰ ⁵⁵⁵ ⁵⁶⁰ ⁵⁶⁵ ⁵⁷⁰ ⁵⁷⁵ ⁵⁸⁰ ⁵⁸⁵ ⁵⁹⁰ ⁵⁹⁵ ⁶⁰⁰ ⁶⁰⁵ ⁶¹⁰ ⁶¹⁵ ⁶²⁰ ⁶²⁵ ⁶³⁰ ⁶³⁵ ⁶⁴⁰ ⁶⁴⁵ ⁶⁵⁰ ⁶⁵⁵ ⁶⁶⁰ ⁶⁶⁵ ⁶⁷⁰ ⁶⁷⁵ ⁶⁸⁰ ⁶⁸⁵ ⁶⁹⁰ ⁶⁹⁵ ⁷⁰⁰ ⁷⁰⁵ ⁷¹⁰ ⁷¹⁵ ⁷²⁰ ⁷²⁵ ⁵³⁸⁵ ⁵³⁹⁰ ⁵³⁹⁵ ⁵⁴⁰⁰ ⁵⁴⁰⁵ ⁵⁴¹⁰ ⁵⁴¹⁵ ⁵⁴²⁰ ⁵⁴²⁵ ⁵⁴³⁰ ⁵⁴³⁵ ⁵⁴⁴⁰ ⁵⁴⁴⁵ ⁵⁴⁵⁰ ⁵⁴⁵⁵ ⁵⁴⁶⁰ ⁵⁴⁶⁵ ⁵⁴⁷⁰ ⁵⁴⁷⁵ ⁵⁴⁸⁰ ⁵⁴⁸⁵ ⁵⁴⁹⁰ ⁵⁴⁹⁵ ⁵⁵⁰⁰ ⁵⁵⁰⁵ ⁵⁵¹⁰ ⁵⁵¹⁵ ⁵⁵²⁰ ⁵⁵²⁵ ⁵⁵³⁰ ⁵⁵³⁵ ⁵⁵⁴⁰ ⁵⁵⁴⁵ ⁵⁵⁵⁰ ⁵⁵⁵⁵ ⁵⁵⁶⁰ ⁵⁵⁶⁵ ⁵⁵⁷⁰ ⁵⁵⁷⁵

varied in accordance with the desires of the shoe manufacturer though it is preferable that the marginal portion of the shoe upper be lasted flat against the insole of the shoe as is usual in the manufacture of such shoes as have their outsoles cement attached directly to their uppers.

- After the completion of the lasting operation and the trimming off of any surplus upper stock which may be present, a plurality of rows of stitching, illustrated at 18 in Figs. 2, 3 and 5 as fair-stitching, is inserted. The thread used for this is composed of soluble material adapted, when treated with a suitable solvent, to form a cement suitable for sole attaching. For this purpose I prefer to use thread composed of cellulose acetate fibres, either alone or in combination with cotton or linen, though thread composed of fibres of other soluble material, for example cellulose nitrate or other cellulose ester or ether, may be used. If a composite thread is used, it may advantageously comprise a core of insoluble material, such as cotton or linen, and an outer layer of cellulose acetate. This fair-stitching preferably passes through the shoe upper and well into but not through the insole, as illustrated on a much enlarged scale on Fig. 3. It may be inserted by a fair-stitching machine of known type, for example by a machine such as that illustrated in Letters Patent of the United States No. 562,335, granted June 16, 1896, on an application filed in the name of Edwin F. Mower, the machine preferably being provided with a thread inserting tool of the character more fully disclosed in Letters Patent of the United States No. 584,952, granted June 22, 1897, on another application filed in the name of said Mower. Such machine, as illustrated in Fig. 4, is provided with an awl 20 arranged to pierce the work for the reception of the thread and also, by a transverse movement, 40 to feed the work which is presented to a presser foot 22 and a gage 24. The machine is also provided with a thread guide 26 the end portion of which controls the thread 28 as it passes down toward the work and with a thread inserting tool 45 30 the end surface of which forces loops of thread down into the holes formed in the work by the awl. For further details of the machine the reader is referred to said Letters Patent of the United States No. 562,335 and to the related Letters Patent No. 563,871, granted July 14, 1896, on still another application of said Mower.
- Preferably this fair-stitching machine is provided with a work support comprising a jack terminating in a last pin which is received in the thimble hole of the last as illustrated at 32 in Fig. 4. The details of such jack are not illustrated herein as they form no part of the present invention. The jack may be, if desired, of the kind disclosed in Letters Patent of the United States No. 919,424, granted April 27, 1909, in the name of William H. Cuff.
- After the fair-stitching, preferably arranged in a plurality of rows as indicated at 18 in Figs. 2 and 3, has been inserted a suitable solvent or softener is applied thereto. This may be acetone (assuming the use of cellulose acetate or cellulose nitrate thread) or any other solvent which by acting on the thread will form a suitable cement, or I may use a solvent which itself includes more or less cellulose acetate or cellulose nitrate, for example as disclosed in Letters Patent of the United States No. 1,959,320, granted May 15, 1934, on an application filed in the name of Walter H. Wedger, or No. 1,959,321, granted May 15, 1934, 70 75 on an application also filed in the name of said

Wedger. The marginal portion of the outsole 34, which is to be attached to the shoe bottom, is roughened in the usual way and preferably, though not necessarily, the outsole is molded or conformed to the shape of the shoe bottom. The outsole is applied to the shoe bottom before the solvent or softening material has had time to evaporate and the shoe and sole are placed under pressure, for example in a cement sole attaching machine of the kind disclosed in an application for Letters Patent of the United States Serial No. 636,202, filed October 4, 1932, in the names of Milton H. Ballard et al.

Under some circumstances it may be preferred to apply a coating of pyroxylin cement to the roughened marginal portion of the outsole 34 before the sole is applied to the shoe bottom. This, however, is not ordinarily necessary and should be done only when unusual conditions make it worth while. In such cases it is optional with the shoe manufacturer whether this coating of cement on the marginal portion of the sole is activated with softener before the sole is applied to the shoe bottom. If this is done, however, it may, without departing from the scope of my invention, take the place of the softener applied to the stitching inserted in the overlasted marginal portion of the shoe bottom.

Having described my invention, what I claim as new and desire to secure by Letters Patent of the United States is:

1. That improvement in methods of securing together pieces of stock which comprises inserting fair-stitching from one side only of one or more layers of stock using a thread composed at least in part of soluble material which upon treatment with a suitable solvent will form cement, treating the fair-stitching with such a solvent thereby forming cement, and pressing the stock which is to be cemented to the fair-stitched stock against said cement.

2. That improvement in methods of securing together pieces of stock which comprises fair-stitching one or more layers of stock with thread composed at least in part of a soluble cellulose derivative, said stitching being inserted from one side only of the stock and not passing completely therethrough, treating the fair-stitching with a solvent for said cellulose derivative thereby forming cement, and pressing the stock which is to be cemented to the fair-stitched stock against said cement.

3. That improvement in methods of securing together pieces of stock which comprises fair-stitching one or more layers to stock with a thread composed at least in part of cellulose acetate, said fair-stitching being inserted from one side only of the stock and not passing completely therethrough, treating the fair-stitching with a solvent for cellulose acetate thereby forming cement, and pressing stock which is to be cemented to the fair-stitched stock against said cement.

4. That improvement in methods of making shoes which comprises inserting fair-stitching in a part already incorporated in a shoe without passing through to the inside of the shoe and using a thread composed at least in part of readily soluble material which upon treatment with a suitable solvent will form cement, treating the fair-stitching with such a solvent thereby forming cement, and pressing a part which is to be cemented to the fair-stitched part against said cement.

5. That improvement in methods of making

- shoes which comprises inserting fair-stitching in a part already incorporated in a shoe using a thread composed at least in part of a soluble cellulose derivative, treating the fair-stitching with a solvent for said cellulose derivative thereby forming cement, and pressing a part which is to be cemented to the fair-stitched part against said cement.
6. That improvement in methods of making shoes which comprises inserting fair-stitching peripherally of a shoe part with a cellulose ester thread, treating the fair-stitching with a solvent for the cellulose ester and thereby forming cement, and pressing a shoe part which is to be cemented to the fair-stitched part against said cement.
7. That improvement in methods of making shoes which comprises inserting fair-stitching peripherally of a shoe part without passing completely through said part using a cellulose acetate thread, treating the fair-stitching with a solvent for cellulose acetate and thereby forming cement, and pressing a shoe part which is to be cemented to the fair-stitched part against said cement.
8. That improvement in methods of manufacturing shoes which comprises stitching the overlasted marginal portion of a shoe bottom with a thread composed at least in part of readily soluble material which upon treatment with a suitable solvent will form cement, treating the stitching with such a solvent thereby forming cement, and pressing a sole on the shoe bottom.
9. That improvement in methods of manufacturing shoes which comprises fair-stitching the overlasted marginal portion of a shoe bottom with a thread composed at least in part of readily soluble material which upon treatment with a suitable organic solvent will form cement, treating the stitching with such a solvent thereby forming cement, and pressing a sole on the shoe bottom.
10. That improvement in methods of manufacturing shoes which comprises stitching the overlasted marginal portion of a shoe bottom with a thread composed at least in part of cellulose acetate, treating the stitching with a solvent for cellulose acetate thereby forming cement, and pressing a sole on the shoe bottom.
11. That improvement in methods of manufacturing shoes which comprises inserting stitching into the overlasted portion of the upper and the body of the insole of a lasted shoe using thread composed at least in part of readily soluble material which upon treatment with a suitable solvent will form cement, treating the stitching with such a solvent thereby forming cement, and pressing a sole on the shoe bottom.
12. That improvement in methods of manufacturing shoes which comprises inserting several rows of stitching into the overlasted portion of the upper of a lasted shoe using thread composed at least in part of readily soluble material which upon treatment with a suitable solvent will form cement, treating the stitching with such a solvent thereby forming cement, and pressing a sole on the shoe bottom.
13. That improvement in methods of manufacturing shoes which comprises inserting several rows of stitching into the overlasted portion of the upper and the insole of a lasted shoe using thread composed at least in part of cellulose ester, treating the stitching with a solvent for said cellulose ester thereby forming cement, and pressing a sole on the shoe bottom.
14. That improvement in methods of manufacturing shoes which comprises inserting several rows of stitching in the overlasted marginal portion of a shoe upper and the marginal portion of the insole of a lasted shoe using a thread composed at least in part of cellulose acetate, treating the stitching with a solvent for cellulose acetate thereby forming cement, applying a sole to the shoe bottom, and maintaining the sole and shoe under pressure while the cement is setting.
15. That improvement in methods of manufacturing shoes which comprises inserting several rows of stitching in the overlasted marginal portion of a shoe upper and the marginal portion of the insole of a lasted shoe using a thread composed at least in part of cellulose acetate, treating the stitching with acetone thereby forming cement, applying a sole to the shoe bottom, and maintaining the sole and shoe under pressure while the cement is setting.
16. That improvement in methods of manufacturing shoes which comprises inserting several rows of fair-stitching in the overlasted marginal portion of the upper of a lasted shoe using thread composed at least in part of a readily soluble material which upon treatment with a suitable solvent will form cement, treating the fair-stitched shoe bottom with such a solvent thereby forming cement, applying a sole to the shoe bottom, and maintaining the shoe and sole under pressure while the cement is setting.
17. That improvement in methods of manufacturing shoes which comprises inserting several rows of fair-stitching in the overlasted marginal portion of the upper of a lasted shoe using thread composed at least in part of cellulose ester, treating the fair-stitched shoe bottom with a solvent for said cellulose ester thereby forming cement, applying a sole to the shoe bottom, and maintaining the shoe and sole under pressure while the cement is setting.
18. That improvement in methods of manufacturing shoes which comprises fair-stitching the overlasted marginal portion of a shoe bottom with a soluble cellulose derivative thread while the shoe is on a last, treating said thread with a solvent for said cellulose derivative thereby forming cement on the shoe bottom, applying a sole to the shoe bottom, and maintaining the shoe and sole under pressure while the cement is setting.
19. That improvement in methods of manufacturing shoes which comprises fair-stitching the overlasted marginal portion of a shoe bottom with cellulose ester thread while the shoe is on a last, treating said thread with a solvent for the cellulose ester thereby forming cement on the shoe bottom, applying a sole to the shoe bottom, and maintaining the shoe and sole under pressure while the cement is setting.
20. That improvement in methods of manufacturing shoes which comprises fair-stitching the overlasted marginal portion of a shoe bottom with cellulose acetate thread while the shoe is on a last, treating said thread with a solvent for cellulose acetate thereby forming cement on the shoe bottom, applying a sole to the shoe bottom, and maintaining the shoe and sole under pressure while the cement is setting.
21. That improvement in methods of making shoes which comprises securing a shoe upper in lasted relation to an insole and last, without withdrawing the last fair-stitching the overlasted marginal portion of the upper with thread comprising a soluble cellulose derivative, thereafter treating the cellulose derivative thread with a solvent therefor and thereby forming cement on

the shoe bottom, applying a suitably prepared sole to the shoe bottom, and maintaining the shoe and sole under pressure while the cement is setting.

- 5 22. That improvement in methods of making shoes which comprises securing a shoe upper in lasted relation to an insole and last, without withdrawing the last fair-stitching the overlasted marginal portion of the upper with thread comprising a cellulose ester, said fair-stitching extending through the upper but not through the insole, thereafter treating the thread with a solvent for the cellulose ester and thereby forming cement on the shoe bottom, applying a suitably prepared sole to the shoe bottom, and maintaining the shoe and sole under pressure while the cement is setting and thereby cement-attaching the sole.
23. That improvement in methods of making shoes which comprises securing a shoe upper in lasted relation to an insole and last, without withdrawing the last fair-stitching the overlasted marginal portion of the upper with thread comprising cellulose acetate fibres, said fair-stitching extending through the upper and into but not through the insole, thereafter treating the thread with a solvent for cellulose acetate thereby forming cement on the shoe bottom, applying a suitably prepared sole to the shoe bottom, and maintaining the shoe and sole under pressure while the cement is setting and thereby cement-attaching the sole.
24. That improvement in methods of manufacturing shoes which comprises inserting a plurality of rows of fair-stitching in the overlasted marginal portion of a shoe upper using thread

composed partly of a readily soluble cellulose derivative and partly of substantially insoluble material, treating the fair-stitching with a liquid which has no effect on the substantially insoluble material of the thread but is a good solvent for the cellulose derivative and thereby forming cement, applying a sole to the shoe bottom, and maintaining the shoe and sole under pressure while the cement is setting.

25. That improvement in methods of manufacturing shoes which comprises inserting a plurality of rows of fair-stitching in the overlasted marginal portion of the upper but not through the insole of a shoe mounted on a last using thread provided with an outer layer of a cellulose ester and an inner core of cellulose, treating the fair-stitching with a liquid which has no effect on cellulose but is a good solvent for said cellulose ester thereby forming cement, applying a sole to the shoe bottom, and maintaining the shoe and sole under pressure while the cement is setting.

26. That improvement in methods of manufacturing shoes which comprises inserting a plurality of rows of fair-stitching through the overlasted marginal portion of the upper and into but not through the insole of a shoe mounted on a last using thread provided with an outer layer of cellulose acetate and an inner core of cellulose fibre, treating the fair-stitching with a liquid which has no effect on cellulose but is a good solvent for cellulose acetate thereby forming cement, applying a sole to the shoe bottom, and maintaining the shoe and sole under pressure while the cement is setting.
